UNITED STATES PATENT OFFICE.

HANS HANSEN, OF MASPETH, NEW YORK, ASSIGNOR TO EASTERN TUBE & TOOL COMPANY, OF BROOKLYN, NEW YORK, A CORPORATION OF NEW YORK.

ARMOR-WINDING MACHINE.

1,396,197.

Specification of Letters Patent.

Patented Nov. 8, 1921.

Application filed October 3, 1919. Serial No. 328,241.

To all whom it may concern:

Be it known that I, HANS HANSEN, a subject of the King of Norway, and a resident of Maspeth, county of Queens, and State of New York, have invented certain new and useful Improvements in Armor-Winding Machines, of which the following is a specification, reference being had to the accompanying drawings, forming a part

10 thereof.

My invention relates to armor winding machines and its objects are to improve upon such machines as have been available heretofore, and to provide a simple and inexpensive machine which is efficient in operations and which may be used for winding armor onto an insulated wire or into a flexible tube.

In order that my invention may be thoroughly understood I will now proceed to describe the same in the following specification and then point out the novel features thereof in appended claims.

Referring to the drawings:

25 Figure 1 is a central sectional front elevation of a machine made according to and embodying my invention.

Fig. 2 is a plan view of the same apparatus.

30 Fig. 3 is a sectional elevation of a portion of the machine with a wire or mandrel running through it and with a portion of the completed armor shown in section.

Fig. 4 is an enlarged sectional elevation 35 through the crimping rolls.

Like characters of reference designate corresponding parts in all the figures.

10 designates the side frames of the machine to which is affixed a cross frame 11 and a top 12. A saddle bracket 13 is fastened to the cross frame and this supports a bearing 14 for a shaft 15. Another bearing 16 for this shaft is secured to one of the side frames and outside of this bracket on the shaft are fast and loose pulleys 17 and 18. A bevel gear 19 is affixed to the other end of this shaft.

50 A hollow spindle 20 runs through bearings in the saddle bracket 13 and in the cross frame 11. Splined to it is a bevel gear 21 which meshes with gear 19 on the underside thereof. 22 is a grooved collar secured to this spindle below the saddle bracket. The forked ends of a lever 23 engage this collar. The lever is pivoted at

24 in a bearing which depends from the saddle bracket. To its other end is connected an adjusting rod 25. The upper end of the adjusting rod is threaded and provided with a nut 27 supported against vertical movement in a forked bracket 26 affixed to one of the side frames, by means of which the vertical position of the hollow spindle 20 may be raised or lowered manually.

30 is another bevel gear affixed to the hollow pedestal 31 of a rotary table 32. This gear meshes with the upper part of gear 19. The periphery of the table 32 is circular and is guided by rollers 33 suitably mounted in the frame top 12. The center of the rotary table is bored to receive the hub 34 of a reel core 35 which is mounted to rotate as the strip 53 is wound off. The flanges of the reel are designated by 36. 37 75 is a ball bearing interposed between the under flange 36 and the rotary table 32.

70 Mounted on the rotary table 32 is a stand 40 to which is hinged at 41 a supporting frame 42 in which are rotatably mounted a pair of crimping rolls 43, one of which is vertically adjustable in relation to the other.

75 In the stand 40 is a slidable bolt 44 which is arranged to engage a slot 38 in the edge of the lower reel flange 36.

80 50 is a grooved guide sheave pivotally mounted in a bearing 51 depending from the saddle bracket 13 and holding the sheave in such a position that a wire or cable 52 may be led from a reel (not shown), 90 up through the center of the hollow spindle 20. The metallic strip which is to be wound onto this wire or into a flexible tube, is designated by 53 and the finished armor by 54.

95 The operation of this apparatus is as follows:—The crimping roll frame is first swung down about its hinges into the position in which it is shown in dotted lines at 42^A, and the bolt 44 moved into the slot 38. Then when shaft 15 is rotated, the reel will be driven through gears 19 and 30, table 32 and bolt 44, about the spindle 20 which then rotates idly in the opposite direction as it is driven by gears 19 and 21. This rotation of the reel is utilized for the purpose of winding up a desired amount of flat metal strip onto the reel.

100 105 110 After this, the bolt 44 is moved out of en-

gagement with the reel flange and the stand 42 raised to its upright position. Then the strip 53 is passed under the lower crimping roller 43, and between it and the upper one 5 and led to the upper end of the spindle 20 and to the wire 52 where it projects through the spindle. The crimping rollers are brought together so that they bend the strip 53 transversely into some such shape as that 10 shown at 53^A in Fig. 4. The wire 52 is usually covered with a suitable insulation.

As the machine is driven the reel and crimping rollers will rotate in one direction and the spindle in the opposite direction.

15 Successive layers of the strip will overlap about one-half the width of the strip and this will cause the finished armor to advance due to the fact that the center or crimped portion of the strip 53 will continually 20 wedge itself, during the winding movement, between the upper end of the spindle 20 and the lower edge of the preceding convolution of the strip. Where it is wound around a wire, it will grip the wire on its insulating 25 cover and cause it to advance. The rotation of the spindle prevents the strip from gripping it or sticking.

The vertical position of spindle 20 may be adjusted in a manner previously described, to vary the position of the point of winding relatively to that of the crimping rolls to thereby get the desired relative position of successive convolutions of the winding and to obtain the desired amount of 35 overlap.

When the machine is used to make a flexible armored tube, the wire is omitted and the spindle adjusted until the desired amount of overlap is obtained.

40 While I have shown and described the machine as built and operated with the spindle 20 in a vertical position, this is in no way essential and I do not intend to limit myself to this or any other specific detail 45 of construction. In fact, I intend no limitations other than those imposed in the following claims.

What I claim is:

1. An armor winding machine comprising 50 a rotary spindle, a rotary disk concentric with the spindle, a strip reel rotatively mounted in axial alinement with the spindle, means for driving the spindle and the disk in opposite directions, and a pair of strip 55 crimping rolls adapted to have fixed or moving relation with said reel and mounted to travel with the disk.

2. An armor winding machine comprising a rotary spindle, a rotary disk concentric 60 with the spindle, a strip reel rotatively mounted thereon in axial alinement with the spindle, means for driving the spindle and the disk in opposite directions, a pair of strip crimping rolls adapted to have fixed or moving 65 relation with said reel and mounted to

travel with said disk around the spindle and means for adjusting the spindle longitudinally in relation to said crimping rolls.

3. An armor winding machine comprising 70 a rotary spindle, a rotary disk concentric with said spindle, a strip reel rotatively mounted thereon in axial alinement with the spindle, means for driving the spindle and the disk in opposite directions, a frame pivotally connected with said disk, a pair of strip crimping rolls mounted in said frame, and means for locking the disk and the reel together.

4. An armor winding machine comprising 80 a rotary spindle, a rotary disk concentric with said spindle, a strip reel having flanges, said reel being rotatively mounted on said disk, means for driving the spindle and the disk in opposite directions, a stand affixed to said disk, a frame pivoted to said stand, a pair of strip crimping rolls mounted in said frame, and a bolt in said stand slideable into engagement with one of said reel flanges.

5. An armor winding machine comprising 90 a rotary spindle, a rotary disk concentric with said spindle, a strip reel having flanges, said reel being rotatively mounted on said disk, means for driving the spindle and the disk in opposite directions, a frame connected with the disk beyond the peripheries 95 of the reel flanges, and a pair of strip crimping rolls with their axes parallel to each other and normal to that of the spindle, mounted to travel with said disk around the 100 spindle and adapted to have fixed or moving relation with the reel.

6. An armor winding machine comprising a rotary spindle, a rotary disk concentric 105 with said spindle, a strip reel having flanges, said reel being rotatively mounted on said disk, means for driving the spindle and the disk in opposite directions, a frame connected with the disk beyond the peripheries 110 of the reel flanges, a pair of strip crimping rolls with their axes parallel to each other and normal to that of the spindle, mounted to travel with said disk around the spindle and adapted to be held in fixed relation with the flanges of said reel, means for adjusting 115 the relative positions of said rolls and means for adjusting the spindle longitudinally in relation to said crimping rolls.

7. An armor winding machine comprising 120 a hollow rotary spindle, a rotary disk concentric with said spindle, a strip reel rotatively mounted thereon, means for driving the spindle and the disk in opposite directions, and a pair of strip crimping rolls mounted outside of the reel and arranged to 125 travel around the reel or to be held in fixed relation therewith.

8. An armor winding machine comprising 130 a hollow rotary spindle, a rotary disk concentric with said spindle, a strip reel rota-

tively mounted thereon, means for leading a wire through said spindle, means for driving the spindle and the disk in opposite directions, a pair of strip crimping rolls 5 mounted to travel with said disk around the reel and to lead strip material from the reel to the spindle, means for adjusting the spindle longitudinally in relation to said crimping rolls and means for locking the disk and 10 the reel together.

9. An armor winding machine comprising a hollow rotary spindle, a rotary disk concentric with said spindle, a strip reel having flanges, said reel being rotatively mounted 15 on said disk, means for leading a wire through said spindle, means for driving the spindle and the disk in opposite directions, a frame pivotally connected with the disk beyond the peripheries of the reel flanges, a 20 pair of strip crimping rolls with their axes parallel to each other and normal to that of the spindle, mounted in said frame, means for adjusting the relative positions of said rolls, means for adjusting the spindle longitudinally in relation to said crimping rolls 25

and means for locking the disk and the reel together.

10. An armor winding machine comprising a rotary spindle, a rotary disk concentric with said spindle, a strip reel having flanges, 30 one of said flanges being provided with a notch, means for leading a wire through the spindle, the center of said disk being provided with a bore adapted to rotatively support a portion of the strip reel, means for 35 driving the spindle and the disk in opposite directions, a stand affixed to said disk beyond the peripheries of the reel flanges, a frame pivoted to said stand, a pair of strip crimping rolls mounted in said frame with their 40 axes parallel to each other and normal to that of the spindle, means for adjusting the relative positions of said rolls, means for adjusting the spindle longitudinally in relation to said crimping rolls and a bolt in said 45 stand slidable into engagement with the notch in one of said reel flanges.

In witness whereof, I have hereunto set my hand this 2nd day of October, 1919.

HANS HANSEN.
